UNITED STATES PATENT OFFICE

143,544

DESIGN FOR A CROQUET WICKET

George T. Meyer, Milwaukee, Wis.

Application August 30, 1945, Serial No. 121,742

Term of patent 14 years

(Cl. D34—5)

To all whom it may concern:

Be it known that I, George T. Meyer, a citizen of the United States of America, and a resident of Milwaukee, in the county of Milwaukee and State of Wisconsin, have invented a new, original, and ornamental Design for a Croquet Wicket, of which the following is a specification, reference being had to the accompanying drawing, forming a part thereof.

In the drawing:

Fig. 1 is a front elevational view of the croquet wicket embodying the invention;

Fig. 2 is a side elevational view of the wicket; and

Fig. 3 is a top view of the wicket.

I claim:

The ornamental design for a croquet wicket, as shown.

GEORGE T. MEYER.
